PUSH BUTTON

Filed Jan. 10, 1919

Fig. 1.

Fig. 2.

Inventor;
Lee P. Hynes,

By E. M. Bentley
Attorney.

UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

PUSH BUTTON.

Application filed January 10, 1919. Serial No. 270,517.

To all whom it may concern:

Be it known that I, LEE P. HYNES, a citizen of the United States, residing at Albany, in the county of Albany and State 5 of New York, have invented certain new and useful Improvements in Push Buttons, the following being a full, clear, and exact disclosure of the one form of my invention which I at present deem preferable.

10 For a detailed description of the present form of my invention, reference may be had to the following specification and to the accompanying drawing forming a part thereof, wherein—

15 Fig. 1 is a horizontal and

Fig. 2 a vertical section of my device.

My invention relates to a push button particularly designed for use on railway vehicles in connection with signaling systems, 20 including a bell or buzzer for notifying the motorman when a passenger wishes to get off. For this special purpose no prior push button that I am acquainted with is entirely satisfactory, particularly with the metal 25 cars and high voltages now employed. Such buttons are usually inserted on the post capping between the windows or in a similar location convenient to the passengers' reach. It is important to have a small, attractive 30 button, mechanically strong and well insulated electrically, in view of the high voltage now generally used on signaling systems. As all the wiring is hidden behind 35 the post capping or sheathing of the car it is essential that the button be capable of ready connection to and disconnection from the wiring without removal of the post capping. It is also important that the part of the button extending back into the side of the car 40 be as small as possible, since in most cars the space for receiving it is limited. Yet the button and its parts must be mechanically strong and highly insulated in spite of the restriction in size. To meet these requirements I have devised the button of the present application.

Referring to the drawing, A represents the capping of the post B. Although here shown as made of wood, the post and capping may be of metal, so far as my button is concerned, since it does not depend for insulation on the wood and may be applied without change to a metal post and a metal capping. C is a moulded block of insulating material cylindrical in form with a seat-

ing flange D projecting laterally about midway of its length. E is a metal shell enclosing cylindrical block C which is secured in place within the shell by a washer F, that is secured in turn by upsetting the edge of the 60 shell over it from the outside.

In the front face of block C a cavity G is formed and concentric with that cavity is a round opening in the face of the shell containing the flanged button H. The cavity 65 G forms a chamber which receives the inner enlarged portion of said button. The shell is also formed with perforated ears J, J, by which it may be screwed to the capping. The rear end of the button is flanged and 70 rounded, the flange being seated against the inside surface of the shell with only the small pushing extension projecting outside. A helical spring O is seated in a circular groove in the bottom of cavity G, the outer 75 end of the spring carrying a circular contact disc K that bears against the rounded end of the button H. Thus the parts of the device are readily assembled and held together without screws. The button H will 80 be placed in its receiving hole in the shell; then the block C with the spring O and disc K in place therein will be inserted in the shell and secured by the washer D. Through the block C extend two offset bars P¹ and P², 85 the front ends of these bars being adjacent to contact disc K and their rear ends being offset on each side of a barrier Q that projects from the rear end of block C. These rear ends of the bars P¹, P² are provided with 90 binding screws for the respective circuit-wires which pass up through the post into the cavity S that receives the rear end of the button-structure. The binding screws pass through the offset ends of bars P¹, P² and 95 under recesses in the block C. In use, my device is furnished in permanently assembled condition, it being unnecessary to open it and reassemble it in the car in order to make 100 the electrical connections and place it in operating position. There are merely the two external terminals of bars P¹ and P² to be manipulated; these are connected to the respective lead wires (which will be of sufficient length to reach out in front of the capping) and the device then pushed into its circular receiving recess and secured to the capping by the screws through ears J, J.

By the arrangement described, I secure adequate mechanical strength and insulation 110

that stands a regular shop test of 2000 volts although the block C is at its rear end but five-eighths of an inch in diameter with an over-all length of one and one-quarter inches. Obviously the pressing in of the button H will bring the disc K into contact with the two outer extremities of bars P¹, P² and close the electric circuit through the wires connected to said bars.

10 What I claim as new and desire to secure by Letters Patent is:

1. An electric push button comprising a shell having an opening therein, an insulating block secured within said shell and having a recess in its outer end registering with said opening, a button working in said opening and having an enlarged portion located within said recess, conductor bars embedded within said block and having ends projecting into said recess, a contact piece within said recess and movable independently of said button, and a spring acting to normally press said contact piece and said button away from the projecting ends of said conducting bars, said spring bearing against the

contact piece contiguous to the periphery of the latter.

2. An electric push button comprising a shell having an opening therein, an insulating block secured within said shell and having a recess in its outer end registering with said opening, the inner end of said block having a projection providing an insulating barrier, a button working in the opening of said shell and having an enlarged portion within said recess, conducting bars having ends projecting into said recess the other ends of said conducting bars projecting on opposite sides of said insulating barrier, a contact piece within said recess and movable independently of said button, and a spring acting to normally press said contact piece and said button away from the projecting ends of said conducting bars, said spring bearing against the contact piece contiguous to the periphery of the latter.

Signed at Albany, N. Y., Jan. 7, 1919.

LEE P. HYNES.
